UNITED STATES PATENT OFFICE.

HARVEY H. WEIDNER, OF PLYMOUTH, INDIANA.

PHOTOGRAPH-PRINTING STAND.

1,093,509.

Specification of Letters Patent. Patented Apr. 14, 1914.

Application filed March 3, 1913. Serial No. 751,858.

To all whom it may concern:

Be it known that I, HARVEY H. WEIDNER, a citizen of the United States, residing at Plymouth, in the county of Marshall and State of Indiana, have invented certain new and useful Improvements in Photograph-Printing Stands; and I do declare the following to be a full, clear, and exact description of the invention, such as will enable others skilled in the art to which it appertains to make and use the same.

This invention relates to photography, and more especially to the printing of photographs from the negative plates; and the object of the same is to produce a stand having a hollow body containing the electric lights and having a hole in its top, and an improved construction of carriage movable over said top and either across the hole or away from over it, and held in firm contact with the sensitive paper which overlies the negative.

This and other objects are carried out by constructing the device in the manner hereinafter more fully described, and as shown in the drawings wherein—

Figure 1 is a side elevation of this stand complete, showing the carriage at about the mid-length of its movement in full lines, and showing the top of the stand in dotted lines as tipped to the rear; and Fig. 2 is a front elevation, while Fig. 3 is a plan view thereof. Fig. 4 is an enlarged longitudinal section with the carriage in its foremost or forward position, and Fig. 5 a similar section with the carriage retracted to its rearmost position. Figs. 6, 7 and 8 are cross sections on the lines 6—6, 7—7, and 8—8 respectively of Fig. 4. Fig. 9 is a longitudinal section of one of the guide fingers herein-after referred to.

In the drawings is shown a stand, herein illustrated as comprising legs 1 carrying a hollow body 2 within which is disposed a ruby or orange light 3 and a white light 4, the same in the present instance being illustrated as incandescent lights in circuit with a switch 5 whose switch arm 6 projects through the top 7 of the stand as best indicated in Fig. 4. As usual in devices of this character, especially where they are employed for rapid commercial photograph printing, the electric circuit indicated in diagram in this view is connected up with

a source of power so that when the switch is 55 thrown to the position shown in Fig. 4 the white light 4 is turned on and printing occurs, but when the parts stand as seen in Fig. 5 the switch is at the other extreme and the red or orange light 3 is burning so 60 that the sensitive paper is not fogged. The top 7 of the stand is preferably hinged at 8 in rear of its body 2, and across the front of said top on its under side is a cleat 9 carrying a hook 10 with which is engaged a spring 65 catch 11 attached to or connected with the body in any suitable manner, so that when it engages the same the top is held horizontal as seen in full lines in Fig. 1, but when it is retracted to disengage the hook 10 the 70 top may be turned over as seen in dotted lines in that view and access to the hollow body may be had as for repairing or cleaning the lights. By preference I attach the catch 11 to a narrow door 12 extending 75 across the front of the body and hinged thereto as at 13, and when the catch is disengaged from the hook this door also may be turned down to give greater freedom of and access to the interior. 80

So much of my device as has already been described may be constructed of wood, with suitable hardware, and the whole properly finished and of suitable dimensions.

In the top 7 is an opening designated at 85 14 in Fig. 6, and the edges of said opening are rabbeted as at 15; and within said rabbet may be placed the glass plate or negative if it is of a size to fit the same, or a reducing frame 16 if the plate 17 is smaller than the 90 opening—the frame itself being rabbeted around its inner edge as seen at 18 so that the upper face of the plate 17 shall stand flush with the upper face of the table 7 and the upper face of the reducing frame 16 if 95 the latter be employed.

Pivoted to standards 20 rising from the table top 7 near its rear end are guide rods 21 whose front ends are turned downward through tubes 22 which are rigidly secured 100 in the table top near its front end, and the lower end of said downturned portions 23 carry nuts or stops 24 between which and the lower ends of said tubes are spiral expansive springs 25 whose force is exerted in 105 drawing said downturned portions 23 and the front ends of the rods 21 downward so that normally the latter do not stand quite

parallel with the table top—see Fig. 5. I would give the springs 25 some considerable tension for a purpose yet to appear, and I would dispose the guides 21 near the side edges of the table top 7 so that ample space is left between them. Within this space is located a carriage, comprising a closed top 30 having a handle 31 rising from it, upright sides 32 in which are journaled the pintles 33 of a series of idle rollers 34 standing close to but out of contact with each other and all of equal size, and in which sides 32 are also journaled the pintles 35 and 36 of a spring roller 37, the same being mounted a little higher than the other rollers as best seen in Fig. 4. One pintle 36 of this spring roller is angular, and is normally engaged by a catch 38 pivoted at 39 to the contiguous side 32 of the carriage, so that 20 when this catch is raised the angular pintle can be given additional rotation to increase the tension of the spring within the roller 37, after which the latch will be again dropped into place as shown in Fig. 1. Connected with the spring roller is a belt, here shown as consisting of cords or strings 40, and connected with the forward end of this belt is a mat 41 which is by preference composed of a rather thick but extremely flexible sheet of rubber, the same extending over the top of the various idle rollers, around the front one, and to the rear over the table top to which it is secured as at 42; and as seen in Fig. 8 this mat is of 25 greater width than the opening in the table top, or in the reducing frame if one be employed.

Projecting laterally from the carriage are stub shafts 50 on which are journaled 40 grooved rollers 51 traveling beneath the guide rods 21, and it will be clear that the expansive force of the springs 25 which depresses the front ends of said rods, also causes the depression of said grooved rollers 45 51 and results in bearing the entire carriage down toward the table top and pressing its various rollers onto the mat and the latter onto the paper and negative. Therefore when the carriage is drawn forward so that 50 the bend in the mat grips even a corner or an edge of the sensitive paper, the latter is pressed into close contact with the negative plate 17 and movement between these parts is prevented. The result is that prints made 55 from this machine show no blur which is such a common fault.

Each stub shaft carries a guide finger, best illustrated in Fig. 9. This consists of a shank 52 standing alongside the carriage 60 and having an eye 53 at its rear end loosely mounted on said stub shaft inside its wheel 51, the other end of the shank being upturned as at 54 and carrying a hook 55 whose bill 56 loosely embraces the guide rod 21 and whose inner end is slotted as at 57

and loosely engages a headed pin 58 on the front end of the carriage. The result of this detail of construction is that said carriage at its front end is accurately guided laterally, or in other words held at its proper position between the two longitudinal guide rods 21, while at the same time it is permitted to move over the face of the table top 7 and the plate 17 whether the guide rods 21 are drawn well down through the tubes 22 as seen in Fig. 5, or not, and leaf springs 60 press the hooks down onto said rods as best seen in Fig. 6. One of the upturned portions 54 at the front end of a finger, as on the right side of the carriage, may well be used as a cam or projection which strikes the upper end of the switch arm 6 as indicated in Fig. 4, and if so a spring will retract the arm as indicated in Fig. 5.

With the above construction of parts, the operation of this printing stand is as follows: With one hand the operator lays the sensitive paper over the plate 17 and with the other hand he grasps the handle 31 and draws the carriage forward to the position seen in Fig. 4. As it reaches the forward limit of its movement, the switch arm 6 is thrown so that the white light or lights 4 is or are cut into circuit, and printing commences within the hollow body 2. The operator may now release his grip on the handle 31, as the tension of the springs 25 is sufficient to hold the carriage at any point along its course—despite the tension of the spring within the roller 37. Having given the exposure a sufficient length of time, the operator has but to grasp the handle 31 and move the carriage back—either to its extreme rearmost position as seen in Fig. 5 if the negative and the print be of considerable size, or only part way back as seen in Fig. 3 if he be printing a small picture which will of course overlie the front edge only of the plate 17. The use of a reducing frame for holding small-sized glass negatives is too well known to need repetition here. Attention is directed to the fact that the upturned end 54 of one of the guide fingers is so disposed that it throws the switch as the carriage is moved to the extreme of its forward travel, and releases the switch as soon as the carriage begins its rearward travel—thus turning off the white light and turning on the ruby or orange light quickly. The operator then removes the print and passes it to the fixing bath, and replaces it with another sheet of sensitive paper so that the operation may be repeated. When now it is desired to gain access to the interior of the hollow body 2, he retracts the catch 11 so as to disengage the hook 10, and immediately the entire top 7 may tilt to the position shown in dotted lines in Fig. 1, giving him liberal space in which to reach into said top to clean or repair the bulbs.

What is claimed as new is:

1. In a printing stand, the combination with a framework including a hollow body supported on legs and having an opening across its front, a hinged door adapted to close said opening, a catch carried by said door, a top hinged to the rear of said body and extending beyond its hinge line and having an opening through it where it overlies such body, a cleat across the lower face of the front edge of said top, and a hook carried by said cleat and adapted to be engaged with said catch; of guides carried by said top, a carriage movably mounted on said guides, and a mat secured to the rear portion of said top and adapted to be carried across said opening by the forward movement of said carriage.
2. In a printing stand, the combination with a framework including a hollow body supported on legs, a catch carried by said body, a top hinged to the rear of said body and extending beyond its hinge line and having an opening through it where it overlies such body, and a hook carried by the front of said top and adapted to be engaged by said catch when the top is closed upon the hollow body; of guides carried by said top, a carriage movably mounted on said guides, and a mat secured to the rear portion of said top and adapted to be carried across said opening by the forward movement of said carriage.
3. In a printing stand, the combination with a framework including a hollow body, a top overlying the same and having an opening above said body, and means within the latter for producing light; of standards rising from the rear end of said top, guide rods pivoted at their rear ends to said standards and downturned at their front ends, tubes set in the table top and through which said downturned front ends extend, stops at the lower extremities of said ends, expansive springs between said stops and the lower side of the top, a carriage movable over the table top, rollers thereon beneath said guide rods, and a mat secured to said top and adapted to be spread across the opening therein by the forward movement of the carriage.
4. In a printing stand, the combination with a framework including a hollow body, a top overlying the same and having an opening above said body, and means within the latter for producing light; of guide rods movably connected at their rear ends with said top and having their front ends turned downward and passed through the same, springs drawing said downturned ends normally downward, a carriage movable over said top between said rods, a mat secured to the rear end of the top and adapted to be spread across said opening by the forward movement of the carriage, stub

shafts projecting rigidly from opposite sides of the latter, and wheels on said stub shaft underlying said guide rods, for the purpose set forth.

5. In a printing stand, the combination with a framework including a hollow body, a top overlying the same and having an opening above said body, and means within the latter for producing light; of guide rods movably connected at their rear ends with said top and having their front ends turned downward and passed through the same, stout expansive springs drawing said downturned ends normally downward, a carriage movable over said top between said rods, idle rollers journaled within said carriage, a spring roller journaled within the same across its rear end, a rubber mat secured at its rear end to the back of said table top and passing beneath said idle rollers and around the foremost thereof, a belt connecting said spring roller with the free edge of said mat whereby the latter is drawn around said foremost idle roller when the carriage is moved to the rear and is spread across said opening when the carriage is moved to the front, stub shafts projecting rigidly from opposite sides of the carriage, and wheels on said stub shafts underlying said guide rods, for the purpose set forth.

6. In a printing stand, the combination with a hollow body, a top overlying the same and having an opening above said body, guide rods extending along the sides of said top, means for depressing said rods with yielding force, and means for creating light within said body; of a carriage movable over the table top, a mat attached to the latter and adapted to be spread across the opening in said top by the forward movement of the carriage, stub shafts projecting from the carriage and having rollers underlying said guide rods, a guide finger loosely mounted at its rear end on each stub shaft and having its forward end upturned, a hook carried by said forward end and having a bill at its outer extremity moving over said guide rod and a slot at its inner extremity, and a headed pin in the front end of the carriage with which said slot is engaged.

7. In a printing stand, the combination with a hollow body having an opening in its top, white and ruby lamps within said body, a switch for energizing one or the other, a switch arm projecting through the top, and means for normally moving it to light the ruby lamp; of a carriage movable over the latter, a mat secured to the top and adapted to be spread across the opening therein by the forward movement of the carriage, parallel guide rods carried by said top, guide fingers connected at their rear ends with said carriage and having their front ends upturned, one of the upturned

ends adapted to strike said switch arm when the carriage is drawn forward, hooks connected at their inner ends with the carriage, at their centers with said upturned ends, and having their bills overlying said guide rods, and rollers on the carriage with which said rods engage.

In testimony whereof I have hereunto set my hand in presence of two subscribing witnesses.

HARVEY H. WEIDNER.
